UNITED STATES PATENT OFFICE

148,552

DESIGN FOR A WALKER OR LIKE ARTICLE

Gerald I. Marcus, Kansas City, Mo.

Application July 19, 1946, Serial No. 131,689

Term of patent 3½ years

(Cl. D14—3)

To all whom it may concern:

Be it known that I, Gerald I. Marcus, a citizen of the United States, residing at Kansas City, in the county of Jackson and State of Missouri, have invented a new, original, and ornamental Design for Walker or like article, of which the following is the specification, reference being had to the accompanying drawing, forming part thereof.

Fig. 1 is a perspective view of a walker showing my new design.

Fig. 2 is a plan view thereof.

I claim:

The ornamental design for a walker or like article, substantially as shown.

GERALD I. MARCUS.
